UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A SHOE.

Application filed February 10, 1925. Serial No. 12,331. Term of patent 3½ years.

To all whom it may concern:

Be it known that I, TAUBE DAVIS, a citizen of the United States, and a resident of the city of New York, borough of Manhattan, in the county and State of New York, United States of America, have invented a new, original, and ornamental Design for a Shoe, of which the following is a specification, reference being had to the accompanying drawing, forming part thereof, wherein the shoe is distinguished by an ornamental multiple bow substantially at the instep, the same being provided with ornamental metallic members matching in color, the ornamental metallic member forming part of the heel.

The figure is a perspective view of a shoe showing my new design.

What I claim is—

The ornamental design for a shoe substantially as shown and described.

TAUBE DAVIS.
